UNITED STATES PATENT OFFICE.

WILLIAM S. O'BRIEN, OF SAN FRANCISCO, CALIFORNIA.

DESIGN FOR A SPOON.

SPECIFICATION forming part of Design No. 22,301, dated March 21, 1893.

Application filed December 13, 1892. Serial No. 455,077. Term of patent 7 years.

To all whom it may concern:

Be it known that I, WILLIAM S. O'BRIEN, a citizen of the United States, residing at San Francisco, in the county of San Francisco and State of California, have invented a certain new and original Design for Spoons, of which the following is a specification.

My design is for the ornamentation of the bowl of a spoon, and the leading feature thereof is the novel shape or exterior configuration of the bowl, which is illustrated in the accompanying drawings, in which—

Figure 1 is a plan view of a spoon having my design applied thereto. Fig. 2 is a side view thereof, and Fig. 3 is a front end view.

As shown by such drawings, the bowl, A, is so shaped that whether viewed from either side, or from the front, it suggests by its appearance a Spanish vessel of the fifteenth century,—such for instance as the *Santa Maria*, in which Columbus crossed the Atlantic on his voyage of discovery. In executing the design the rim of the bowl near its ends is raised, as at 2 and 3, to suggest the elevated decks at the bow and poop of the vessel. At one end of the bowl there is a projecting rib, 4, which represents the rudder, and at the opposite end

of the bowl there is another rib, 5, which represents the stem of the vessel. At 6, 6, are holes or recesses which represent the hawse holes.

The interior or obverse of the spoon bowl made according to my design, makes a convenient surface on which to execute an ornamental design, which should be in harmony with the design of the exterior of the bowl; and such a design is shown in Fig. 1, where, upon the bowl of the spoon there appears a representation of the *Santa Maria* undersail, and a likeness of Columbus. In addition to such representations there are views of the Manufactures and Liberal Arts Buildings, and the United States Government Building, which are now constructed for the Columbian Exposition to be held in 1893 at Chicago. 45

What I claim is—

The design for a spoon substantially as shown and described.

In testimony whereof I affix my signature in presence of two witnesses.

WILLIAM S. O'BRIEN.

Witnesses:

ROBERT MCELROY,
P. A. PIODA.
